United States Patent Office

Des. 224,133
Patented July 4, 1972

224,133

SINK PAD HOLDER OR THE LIKE

James B. Swett, Barrington, R.I., assignor to Dart
Industries Inc., Los Angeles, Calif.

Filed Dec. 11, 1970, Ser. No. 26,413

Term of patent 14 years

Int. Cl. D7—07
U.S. Cl. D44—1

FIG. 1

FIG. 2

FIG. 3

FIG. 4

FIG. 1 is a top plan view of a sink pad holder or the like showing my new design;

FIG. 2 is a front elevational view thereof;

FIG. 3 is a side elevational view thereof; and,

FIG. 4 is a bottom plan view thereof.

I claim:

The ornamental design for a sink pad holder or the like, substantially as shown.
